(57) **CLAIM**

The ornamental design for a frameless portable suspension system, as shown and described.

DESCRIPTION

FIG. 1 is a rear perspective view of a frameless portable suspension system showing our new design;
 FIG. 2 is a rear elevational view thereof;
 FIG. 3 is a front elevational view thereof;
 FIG. 4 is a left side elevational view thereof;
 FIG. 5 is an enlarged fragmentary view taken from area 5 in FIG. 1, which shows the detail of one of the ground anchors connected to the bottom corner of the net;
 FIG. 6 is an enlarged fragmentary view taken from area 6 in FIG. 1, which shows in detail the upper end of one of the telescoping poles connected to the upper corner of the net;
 FIG. 7 is an enlarged fragmentary view taken from area 7 of FIG. 1, which shows in detail the telescoping connection portion of one of the telescoping poles;
 FIG. 8 is an enlarged fragmentary view taken from area 8 in FIG. 1; which shows in detail the lower end of one of the telescoping poles together with one of the ground anchors and high-strength straps;
 FIG. 9 is a top plan view of the overall design;
 FIG. 10 is an enlarged fragmentary view taken from area 10 of FIG. 1, which shows in detail the connection section of the telescoping pole together with the upper end of the adjustable strap; and,
 FIG. 11 is an enlarged fragmentary view taken from area 11 of FIG. 1, which shows in detail the lower end of one of the adjustable straps connected to the ground anchor.
 The broken lines shown in FIGS. 1-11 are included for the purpose of illustrating environmental elements only and form no part of the claimed design.
